UNITED STATES PATENT OFFICE.

ERNEST SCHULTZ, OF EAST MELBOURNE, VICTORIA, AUSTRALIA.

RESILIENT WHEEL.

Application filed January 18, 1923, Serial No. 613,492, and in Australia February 15, 1922.

This invention relates to improvements in resilient wheels and has been devised in order to provide a resilient wheel of greater utility than those at present in use.

5 The invention is applicable to resilient wheels, the treads of which are suspended on air and preferably to that class of resilient wheel having a plurality of spaced cylinders in continuous air communication with each 10 other and having pistons operating therein and outwardly against concave surfaces on rim members and the tread ring of the tyre.

The wheels of this type at present in use are defective for the reason that no means 15 are provided for immediately creating sufficient air pressure in the cylinders to effectively and automatically suspend the load simultaneously with the rotation of the wheels.

20 This invention has been devised in order to overcome this defect and to provide cheap, simple and effective mechanism the essential characteristics of which will be herein-after described.

25 I have found in practice that it is essential in order to provide sufficiently increased air pressure to support the load, that an automatic air pumping device be employed and such a mechanism forms the salient feature of this invention.

30 The basic principle underlying this invention consists of means comprising essentially two piston elements so arranged that when the piston head moves outwardly by centrifugal force or with the help of auxiliary springs air is drawn by the pumping effect into the inner piston and through a suction valve against the inner end of the outer or main piston and when the auxiliary piston 35 returns the air is delivered to the passage connecting all the cylinders of the wheel through a delivery valve, thus an air pumping action takes place which functions so that the main piston is flexibly forced out 40 against the rim members of the discs and the wheel is suspended on air at a pressure capable of being continuously and automatically maintained as the wheel revolves.

45 A further essential feature consists in forming the inner pumping piston or element substantially smaller than the main or outer piston or element the latter element floating on the air pressure created by the pumping member and carrying any weight

55 with a maximum flexibility to absorb any shocks that may be imparted the air pressure in the continuous passage being displaced and transmitted around the wheel so that a plurality or all of the pistons are affected until a shock is absorbed. 60

A further essential feature consists in arranging the pistons in each cylinder so that when the wheel turns the inner or pumping piston head is thrown out by centrifugal force and air is drawn by the suction through 65 holes at the outer end of said piston, and on the rotation the air is forced through the delivery valve of the main piston to an air passage common to all the cylinders and the wheel floats on the air in said passage. 70

A further essential feature consists in the arrangement of the parts whereby the pumping pistons remain inactive when the pressure in the passage common to all the cylinders is equal to the load but on the imparting of a shock or jar to the wheel all the pistons are affected, being all pushed inwardly equally either by the tread ring or the disc rim members and the air in the passage common to all the cylinders is automatically relieved of excess pressure by the return of the pistons to normal position. 75

80 A further essential feature embodied in the invention consists in the arrangement of a rubber or other buffer pad between the floor of the pumping piston and the floor of the main piston and this buffer takes sudden shocks or jars that may be imparted to the rim and ensures silent running.

85 In order that the invention may be more readily understood it will now be described with reference to the accompanying drawings in which:—

Figure 1 is a side elevation partly in section of a wheel constructed according to this 90 invention.

Figure 2 is a transverse section of one-half 95 of the wheel on a larger scale than that shown in Figure 1, and

Figure 3 is a view in vertical central section of one of the cylinders and parts thereof embodied in the invention.

Figure 4 is a sectional view on line A—A of Figure 1.

According to this invention the hub 1 is 100 fitted on both sides with discs 2 suitably bolted at 3 in spaced relation to each other and these discs 2 at their outer edge are

inturned as at 4 towards each other and fitted with rim members 5, the inner surface of which is formed with spaced concave surfaces 6 of a number corresponding 5 to the number of air cylinders 7 employed.

A plurality of cylinders 7 mounted or formed on a continuous casting 8 having a continuous air passage 9 is provided and these cylinders 7 all communicate with the 10 air passage 9, the casting 8 being spaced as at 10 from the hub 1 and is not connected to any part of the wheel other than the said cylinders.

These cylinders 7 extend outwardly and 15 radially within the discs 2 towards but not to the rim members 5 and receive an air piston or pump the main piston 11 in its normal or inner position extending nearly to the inner end of the cylinder.

20 Each main piston 11 extends past the outer end of its cylinder 7 which is open at the outer end 14, being provided with side extensions 15 or a rim adapted to bear against the concave surfaces 6 of the rim members 25 5 of the discs 2 and near the inner end of the said main piston 11, a piston ring 16 or rings are fitted in a groove 17 in the piston which works flush with the internal bore of the cylinder 7.

30 Each main piston 11 is hollow being closed at its inner end at 8^a except for a passage 18 normally closed by a spring controlled delivery valve 19, said passage leading from a hollow pumping piston 21.

35 The valve 19 operates inwardly towards the air passage 9 and is contained in a screw cap 19^a in the floor 8^a of the main piston and is formed with a chamber 19^b, while a spring 19^c operates against the valve being disposed around the valve stem.

Each pumping piston 21 is hollow and is closed at its inner end or floor 22 by a screw cap 23 forming a valve box.

40 A hard rubber or other suitable buffer 45 ring 25 is seated on the floor 8^a of the main piston 11 and is formed with a passage 24 to allow of communication with the passage 18 and the valve chamber 26 of the hollow pumping piston 21, and this buffer takes 50 sudden shocks or jars that may be imparted to the rim and maintains silent running.

The buffer 25 is normally held hard down on the floor or base of the outer piston.

55 The valve chamber 26 is formed centrally in the screw cap 23 of the pumping piston 21 and to allow the passage of air from the inner pumping piston 21 to the valve chamber 26 a passage 27 is provided in the outer end of the screw cap 23 and this passage is normally closed by an inlet valve 28 controlled by the spring 29, surrounding the lower stem of said valve.

60 The inner piston 21 at the outer end or head communicates with the atmosphere by 65 one or a plurality of holes 30 and this inner

piston 21 works flush in the main piston, the latter being internally grooved if desired to receive graphite or other lubricant.

Each inner pumping piston 21 is formed with a head 31, connected at 31' to the piston 21 and curved at the outer end 32 and adapted to always exert outward pressure against concave surfaces 33 on the inner periphery of the tread ring 34 which is concentric of, and spaced from, the rims 5 on the discs 2 it being understood that the pistons operate between the discs 2 above described.

70 In order to accelerate the outward force of the inner pumping piston 21 auxiliary 80 springs 35 are provided operating against its head as at 36 and received in the recess 37 formed on the inner surface of the outer piston.

75 The inner portion of the tread ring 34 85 may be formed of a plurality of abutting metal segments 38 with strengthening webs 39 if so desired to ensure rapid replacement of any part and a fibre or other ring 39^a may be fitted to the hub 1 inside the disc to take the thrust.

80 In operation when the wheel turns the inner or pumping piston head 31 is thrown out by centrifugal force with the assistance 90 of the auxiliary spring 35 and air is drawn by the suction through the holes 30 at the outer end of the piston 21 and through the suction valve 28 into the valve chamber 26 by the partial vacuum created inside said chamber and on rotation the air is forced 100 through the delivery valve 19 to the air passage 9 common to all the cylinders and the wheel thus floats on the air in said passage 9.

85 The load is thus suspended on air which 105 is automatically pumped to the pressure required, so that a positive pressure is maintained by the pumping action of the pistons.

90 The pumps 21 are inactive when the pressure in the passage 9 is equal to the load but on the imparting of a shock or jar to the wheel all the pistons are affected being all compressed equally either by the tread ring or the disc rims and the air in the passage 9 is automatically relieved of excess pressure by the return of the pistons to normal position.

95 I desire it to be understood that various 110 improvements and modifications may be embodied without departing from the spirit and scope of the invention.

120 What I claim as my invention and desire to secure by Letters Patent is:—

125 1. In a resilient wheel a plurality of pairs of pistons each pair of pistons operating in one of a plurality of cylinders spaced around but independent of the hub of the wheel, the head of the pumping pistons bearing against concave surfaces of the tread ring and each main piston having projections 130

- bearing against a concave surface on the rim members of the wheel discs, a suction valve in each pumping piston and a delivery valve in each main piston communicating with an air passage common to all the cylinders, the parts being so arranged that the pumping pistons are inactive when the pressure in the passage is equal to the load but when taking a shock the pistons are affected and pushed inwardly and the air in the passage on the return of the pistons is automatically relieved of excess pressure for the purposes specified.
2. In a resilient wheel a plurality of pairs of pistons each set of two pistons operating in one of a plurality of cylinders spaced around but independent of the hub of the wheel, the head of the pumping pistons engaging concave surfaces of the tread ring and each main piston having projections engaging concave surfaces on the rim members of the wheel discs, a suction valve in the pumping pistons, a delivery valve in the main pistons, and a space externally of the floor of the main pistons communicating with a passage common to all the cylinders the parts being so arranged that the load is suspended on air automatically pumped to the pressure required on the rotation of the wheel.
3. In a resilient wheel a pumping piston and a main piston disposed within radially arranged cylinders spaced from the wheel hub, the pumping pistons being in contact with the tread ring and the main pistons being in contact with the rim members of the wheel discs, auxiliary springs between the pistons, a suction valve on the pumping pistons and a delivery valve on the main piston communicating with an air passage common to all the cylinders the parts being disposed so that on the wheel rotation air is forced through the delivery valves to the air passage so that the wheel floats on the air in said passage.
4. In a resilient wheel a plurality of pairs of pistons each disposed within a cylinder and so arranged that when the pumping piston head moves outwardly by centrifugal force air is drawn by a pumping effect into the main piston through a suction or inlet valve in the floor of the outer or pumping piston, and on return of the pumping piston head the air is delivered to a passage connecting all the cylinders of the wheel through a delivery valve as and for the purposes specified.
5. In a resilient wheel a plurality of pairs of pistons each set of pistons operating in one of a plurality of cylinders spaced around but independent of the hub of the wheel and so disposed that on the revolution of the wheel a pumping action is obtained.
6. In a resilient wheel a plurality of pairs of pistons within cylinders floating around a wheel hub, the pumping piston being substantially smaller than the main piston, the latter being adapted to float on the air pressure created by the pumping member for the purposes specified.
7. In a resilient wheel a plurality of pairs of pistons within cylinders floating around a wheel hub, the pumping piston being formed at the outer end with air inlets and at its inner end with a suction valve, the other or main piston being formed with a delivery valve communicating with a continuous air passage common to all the cylinders for the purposes specified.
8. In a resilient wheel a plurality of pairs of pistons within cylinders floating around a wheel hub, a continuous air communication between all the cylinders, each main piston being fitted with an air delivery valve and each pumping piston being fitted with an air suction valve, a passage at the outer end of each pumping piston, each main piston being provided with projections bearing against rim members on the wheel discs and the outer end of each pumping piston bearing against the inner surface of the tread ring for the purposes specified.
9. In a resilient wheel a plurality of pairs of pistons one working within the other and disposed within radial cylinders spaced and floating around a wheel hub, a passage and a suction valve in the pumping pistons, said valve feeding into the main piston, and a delivery valve in the main piston controlling the delivery of air from said main piston to a passage common to all the cylinders whereby on the outward movement of the pumping piston caused by centrifugal force, air is drawn therein and to the main piston and on the return or inward movement of said pumping piston the air is delivered from the main piston to the continuous passage common to all the cylinders for the purposes specified.
10. A resilient wheel consisting in the combination of a hub fitted with discs forming the wheel sides, the outer edges of the discs being turned inwardly towards each other and being fitted with rim members, the inner surface of each rim member being formed with concave surfaces, a tread ring concentrically of the discs and formed on its inner surface with concave surfaces, the said concave surfaces of the rim members and the tread ring being in radial alignment, air cylinders floating and radially disposed around the hub, air communication between each of the cylinders and an air piston pump in each of the cylinders, said pump comprising two piston elements, one a pump piston element with a suction valve and the other with a delivery valve communicating with the passage common to all the cylinders, a passage in the pumping piston element, a spring to assist the outward movement of the pumping piston member, and extensions

on the piston members bearing respectively against the concave surfaces of the rim members of the discs and the tread ring substantially as described.

5 11. In a resilient wheel, a plurality of pairs of pistons one working in the other and disposed in radial cylinders spaced from and floating around the wheel hub, a passage at the outer head and a suction valve at the 10 inner end of the pumping piston, the head of which engages concave surfaces on the tread ring, the main piston receiving the pumping piston and being provided at the inner end with a delivery valve adapted to 15 deliver the air compressed therethrough to a passage common to all the cylinders substantially as described.

12. In a resilient wheel wherein a plurality of pairs of pistons, one working in the 20 other, and disposed in radial cylinders spaced from and floating around the wheel hub is employed, a passage at the outer head, and a suction valve in a screw cap in the floor of the pumping piston member, a buffer 25 disc between the floors of the two pistons and on the floor of the main piston, a passage between the two piston members closed by said suction valve which opens towards

the main piston against the compression of a spring, the floor of the main piston member being fitted with a screw cap holding a delivery valve operating against the compression of a spring and delivering the air under pressure to a passage common to all the cylinders and a spring between the walls 35 of the inner and outer piston members to assist in the outward throw of the pumping piston by centrifugal force on the turn of the wheel.

13. In a resilient wheel wherein a plurality of pairs of pistons one working in the other and disposed within radially arranged cylinders spaced from and floating around the hub is employed, a passage and a suction valve fitted in the pumping piston, said piston operating against concave surfaces of the tread ring and a delivery valve in the main piston leading to an air passage common to all the cylinders, the said main piston having projections bearing against concave surfaces or rim members with which the inturned portions of the wheeled discs are fitted for the purposes specified.
